MEANS FOR DRAWING OFF OF CIRCULARLY
KNITTED ARTICLESKarel Semotán, Zlin, Czechoslovakia, assignor to
Bata, národní podnik, Zlin, CzechoslovakiaApplication March 24, 1948, Serial No. 16,764
In Czechoslovakia March 31, 1947

12 Claims. (Cl. 66—150)

1 This invention relates to a method of and means for drawing off circularly knitted articles, more particularly stockings, with worked-in or integrally knitted heel and toe pockets, on circular knitting machines, more particularly double-cylinder machines, in which the individual articles of hosiery are knitted in a continuous string. In the production of such articles it is known that difficulties have arisen, particularly in the knitting of a fixed welt, a separating course and the ribbed welt, which follow the toe pocket. In the methods and expedients hitherto known, with the so-called inner drawing-off devices, the presence of tow pockets has hindered the attainment of a uniform withdrawal of the knitting. An irregular tension of the loops that are being formed has occurred, and also of the needles and sinkers, particularly at the two margins of the pockets or pouches, whereby it has hardly been possible to avoid rupture. When knitting the initial row of the next article awkward bunching of loops or double loop formations have occurred in the region of the pockets.

By one known method an attempt has been made to obviate these defects by the fact that in order to equalise the drawing stress occurring in working the pocket, foot-sole needles have been selectively actuated in such a way that upon them, in a few courses, longer loops are knitted, in order to produce, upon the side of the hosiery opposite to a pocket, long or loose loops, and to do this immediately after effecting the production of the pocket in question.

This method however requires a special pattern device for the regularly repeating adjustment of the knitting cams, by which the needles are raised and lowered, and are also heavily stressed. A further disadvantage resides in the fact that after finishing the toe, for the equalisation of the take-off throughout the periphery of the needle ring, a large number of courses of normal knitting, so-called excess running-on courses had to be produced, which were merely useless waste, because they had to be cut off or severed when linking or binding of the toe of the stocking. Also the longer loops of these excess rows were liable to slip off the pushing-up needles of the linking or chain-warp machine, then forming loose hosiery in the region of the chain-warp seam.

Numerous internal drawing-off devices have also already been proposed, which are arranged in the immediate neighbourhood of the needle heads, and serve for drawing off particular parts of the articles, for instance the heel pockets of stockings.

Thus for example an arrangement is known which consists of a draw-off star with a flanged margin, which, after the knitting of a heel or toe pocket, descends for the pressing engagement with the latter. An injury to the article, by the draw-off disc, which is provided with rounded or sharp tips catching in it, and by pressure, is unavoidable. Moreover owing to the presence of the pocket the engagement of the draw-off star in the hosiery is incomplete, and again involves the formation of a relatively large number of courses of excess knitting, which cause waste.

An internal draw-off arrangement has also been suggested which consists of an annular card-wire band, which, after the knitting of one side portion of an article, for instance a heel pocket or the like, by release of a pressure appliance, passes within reach of the entire stocking portion to be drawn off, and continues to exert a drawing-off action until the main pull again takes over the drawing.

The engagement of the card-wire band on the entire periphery of the article is disadvantageous in so far as the card-wire remains prematurely caught in the sole-needle hosiery, and thus hampers the remainder of the drawing off of the pocket. Here again it is impossible to prevent the card clothing damaging the hosiery.

Furthermore an internal drawing-off means is known which consists of a press-thumb, having a circular-shaped and rimmed end which is displaced radially outwards, for the purpose of engaging in the knitting above the pocket that has just been completed, and drawing the knitting downwards for a definite time. Here again the local engagement of the thumb or tappet cam results in an uneven pulling of the sole-needle hosiery, so that there is again the risk of rupturing loops.

Some drawing-off devices have also become known in which steel brushes serve for the internal drawing-off of the knitting, as for instance in French circular knitting machines, in which the individual brushes are hingedly arranged side by side upon a ring, and are lifted in succession, to fall back again forthwith by their own weight and thus re-engage in the knitting for the purpose of drawing it off.

Amongst these internal drawing-off devices there is also a construction for double-cylinder circular knitting machines, the essence of which consists in the fact that the brushes, even before the beginning of the fresh stroke, are positively lifted off the fabric, in order to adapt themselves continuously and automatically to the additional knitted material. By this arrange-

ment the little teeth of the brushes do not injure the material, but on the other hand they tension the knitting uniformly throughout the periphery. In reality however the material undergoes a roughening, which is brought about by the repeated changing of position and by the sudden engagement of the individual brushes in the knitting. A further disadvantage resides in the fact that in knitting the heel and toe pockets, the knitting hanging upon the sole needles and not increasing in length is also drawn off by the brushes.

According to the present invention, all the disadvantages here briefly mentioned of the methods and appliances hitherto known for drawing off circularly knitted goods, particularly stockings with heel and toe pockets worked in, which are knitted in a continuous string on circular knitting machines, particularly double-cylinder machines, can be obviated in a simple manner by drawing off the knitted material hanging on the needles and revolving with the latter mainly in the neighbourhood of the loops that are being formed, this procedure taking the place of the withdrawing of the entire string of knitting, as hitherto usual. As the most advantageous solution of this new method according to the invention it is proposed to draw off the knitted material, in the neighbourhood of the loops that are being formed, with the assistance of bodies which roll upon one another with simultaneous relative sliding of the contact surfaces of the bodies between which the knitting is gripped.

The main feature of the apparatus for carrying out the method according to the invention consists in two bodies having substantially conical surfaces, between which the material is resiliently gripped.

The main advantage of the method and of the device according to the invention is not however to be seen in the fact that the knitting in a known manner is drawn off only in the region of the finish-knitted pocket or at a plurality of points on its periphery, simultaneously or successively, but in the fact that in forming the individual courses of loops each loop rod or pin must run through a place at which it is drawn off, uniformly and continuously, by the means mentioned, from its associated cylinder needle, revolving in a circle.

One embodiment of the invention is illustrated by way of example in the accompanying drawings, in which:

Figure 1 is a diagrammatic representation of two hosiery items produced integrally on a circular knitting machine, with a severing course and with shortened length of the excess courses;

Figure 2 represents diagrammatically the preferred arrangement of the operative rotating conical bodies in relation to one another, which works in the sense of the present invention;

Figure 3 shows in longitudinal section the general arrangement of an interior drawing-off device for carrying out the method upon a double-cylinder circular knitting machine;

Figure 4 illustrates diagrammatically the drawing-off of the circularly revolving material by the operative surfaces of revolution in the immediate neighbourhood of the loop-forming cylinder needles; and

Figure 5 shows an example of the detail construction of a conical drawing-off disc.

In Figure 1, A denotes a heel pouch, B a toe pocket, C the length of the excess or running-on courses of a stocking, which latter may be ma-

terially shortened with the method and device according to the invention, as compared with the twenty to thirty courses of loops previously needed in order to equalise the drawing-off tension. D denotes the fixed welt for the severing row, E the severing row, and F the non-severable welt of the ribbed portion G of the other stocking.

The drawing-off device as a whole, as shown in Figure 3, is arranged in the vicinity of the knitting needles and for the most part in the upper needle cylinder 1. In the lower needle cylinder 2 are provided normal parts of a known two-cylinder machine, such as a sinker ring 3, enclosing sinkers 4, upper and lower sinker rings 5 and 6, and an insertion 7 for drawing off the knitted goods. In the interior of the known stationary drawing-off insertion 7 is rotatably supported a bush 8, which, owing to its flanged rim 9 bearing upon the sinker ring 5 revolving in a circle, is carried round by the latter.

The bush 8 is preferably equipped according to a feature of the invention with a smooth surface of revolution 10, which forms the peripheral surface of a truncated cone, and presents to the knitted fabric 11 revolving in a circle the bearing support necessary for drawing off. As distinguished from the known internal drawing-off devices in double-cylinder machines it accordingly obviates, by the arrangement according to the invention, the friction arising between the stationary drawing-off insertion 7 and the rotating knitted fabric 11.

The mutual local contact of the operative revolving surface of revolution 10 and the knitted material 11 bearing upon it with the operative frusto-conical surface of revolution 12 of a drawing-off disc 13 causes rotation of this disc about the longitudinal axis Y of the latter.

The drawing-off disc 13 may however alternatively be equipped with a drive of its own.

The longitudinal axis Y of the drawing-off disc 13, relatively to the longitudinal axis X of the bush 8, is located eccentrically and at an angle α , so that with the positive or automatic rolling of the drawing-off disc 13 around its longitudinal axis Y on the conical surface 10 of the rotating bush 8, any arbitrarily selected point of contact of the surface of revolution 12 with the surface of revolution 10, for instance the point a in Figure 2, describes a curve, until it arrives at the point a_1 . A change of the angle α , or a change in the position of the disc 13 in relation to that of the bush 8, also results in a change of length of the curve $a-a_1$, and consequently of the drawing-off stroke.

For the purpose of altering the contact conditions, the operative surface of revolution 12 of the draw-off disc 13 may be made concave or roughened, or may be covered with rubber or provided with concentric or spiral grooves 14, as shown in Figure 3. A particularly advantageous construction of the draw-off disc is illustrated in Figure 5, in which the draw-off surface 40 is formed by an independent indiarubber ring 39, which is secured upon a carrying disc 41, for instance by clamping it between the base portion of the disc 41 and a screwed-in bearing face 42.

A ball bearing 15 fitted into the draw-off disc 13 is freely rotatable upon a journal 16, which is screwed into the bevelled end of a holder 17. The holder 17, which is located in the longitudinal axis X of the bush 8, is guided in a bush 18, which is rigidly connected with a fly-off sinker ring 19 known in itself, and revolves with the

latter. Upon a round carrying rod 20 supporting the holder 17 is slipped a cylindrically coiled spring 21, which bears with one end upon the holder 17 and with the other end upon a washer 22, which is located in the bore of the bush 18. The necessary application pressure for the resilient gripping of the knitting between the surfaces of revolution 10 and 12 is determined by suitably selecting the helical spring 21, which may if preferred be arranged even outside the upper needle cylinder 1, for the sake of easier accessibility and to facilitate regulation of the application pressure. In this case the longitudinal displacement of the holder 17 in the axis of the upper needle cylinder might be effected through the medium of a one-armed lever, not shown, pressing with its free end upon the end face of the stepped circular rod 20.

Rotation of the holder 17 about its own axis is prevented by a rigid collar 23 secured upon the rod 20, with notches 24, in which the end of a two-armed lever 25 engages. The lever 25 is rockably supported on a pivot 27 lodged in a longitudinal slot in a stud 26. The lower end of the stud 26 is screw-threaded, and is screwed into the cover plate 28, the position of the stud being secured by a lock nut 29. The engagement of one end of the lever 25 in one of the notches 24 in the rigid collar 23 is ensured by a fitting pin or a pin screw 30, which is secured in the lever 25, bearing against the wall of the stud 26 as soon as the operative surfaces of revolution 10 and 12 come into operative engagement with one another, as shown in Figure 3. Upon the other end of the lever 25 there acts at a suitable time, that is to say, before the beginning of the knitting of the heel or toe pocket, the off-set end 31 of a known lever, part of which is shown, which first presses down the rod 33, guided in the cover plate 28, and provided with a helical spring 32, and thereby also presses down a forked guiding piece 34 against a positioning ring 35, whereby a sprung throw-over cam member 36 is moved away from the upper needle cylinder 1.

This device 31-36, known in itself, for withdrawing the rib needles from the knitting operation in the upper needle cylinder, is utilised at the end of its stroke for lifting the draw-off disc 13 into the interior of the upper needle cylinder 1, by the off-set lever end 31 acting upon the outer end of the lever 25, whereupon the other end of the lever 25 raises the collar 23, together with the rod 20 and the holder 17. The accurate adjustment of the position of the pressure-applying or draw-off point of the two operative surfaces of revolution 10 and 12 in relation to the stitch-forming latch needles that have descended in the lower needle cylinder, as shown in Figure 4, is effected by rotating the holder 17 around its longitudinal axis by hand. At the upper end of the rod 20 is secured a collar 37 with a pointer 38, which in operation indicates the angular position of the draw-off point, which is defined by the curve of contact $a-a_1$ in Figure 2.

The device operates in the following manner: When the formation of the heel or toe pocket is terminated, the machine is changed over from to-and-fro motion to rotary motion. Immediately before the beginning of the circular knitting which now ensues, by means of the known device 31-36, the rib needles of the upper cylinder 1 are re-engaged in the knitting operation, as the upward thrust of the helical spring 32 raises the rod 33. The engagement of the off-set lever end 31 with the outer end of the lever 25 is inter-

rupted, and under the action of the previously compressed spring 21 the holder 17 is displaced downwards in the longitudinal axis of the needle cylinder, so that the operative surface of revolution 12 of the draw-off disc 13 is pressed against the knitting at the place where this surface bears against the surface of revolution 10 of the revolving bush 8, that is to say, along the contact curve $a-a_1$. The draw-off disc 13, with the arrangement illustrated, is then frictionally driven and revolves about its axis Y, with simultaneous relative sliding of the contact surfaces between which the knitting is held, so that it effects a continual drawing off of this knitting, the length of which, in circular knitting, increases uniformly all round the periphery. The worked-in heel and toe portions, which hang upon only half the ring of needles, now also pass between the surfaces of revolution 10 and 12, rolling one upon the other, and are continuously drawn off by them.

The method according to the invention, and the construction of the apparatus described by way of example, are distinguished not only by their suitability for the purpose but also by their simplicity and reliability, the costs of production and operation, as compared with the methods and devices hitherto known, being substantially smaller. The present invention is also suitable for the internal drawing off of the initial courses of a piece of knitting, the number of courses being given by the distance of the needles from the operative surfaces of revolution 10 and 12, without the use of the usual manually operated draw-off hook being necessary, by means of which the knitting has to be drawn off right to its exit from the machine.

The construction of the device is not restricted to the embodiment given by way of example, but admits of various modifications without affecting the essence of the invention. Thus for example a multi-system circular knitting machine also may be equipped with operative surfaces of revolution according to the invention, a draw-off disc being allocated to each working system, and the operative surfaces of revolution of the individual circularly arranged draw-off discs being pressed radially outwards against the fabric by an eccentric drive arranged in the axis of the needle cylinder or by corresponding rod-and-lever mechanism. Experiments have shown that with the new method and apparatus for drawing off the knitting the usual main draw-off appliance, which is arranged underneath the knitting outlet and the lower knitting cylinder, may be entirely omitted. At the beginning of the knitting operation the original length of the knitting between the inner and main draw-off appliances is thereby saved. After the knitting on of a few initial courses of loops, which are drawn off by the device according to the invention, the fixed welt and the severing course may be knitted immediately, whereby again material is saved.

I claim:

1. Means for drawing off circularly knitted fabric, particularly stockings with heel and toe pockets worked in, from a circular knitting machine, such as a double-cylinder machine, wherein individual articles are knitted in a continuous string, comprising: two rotatably mounted bodies with substantially conical surfaces, between which the knitted fabric passes, the bodies being so arranged that their conical surfaces can bear against one another so as to grip the fabric at one point, and means for resiliently urging the

bodies into contact with one another at the said point, the bodies being furthermore so arranged that when they rotate they roll one upon the other and also undergo relative sliding motion at the said point.

2. In a circular knitting machine comprising a needle cylinder, and a revolving sinker ring in the needle cylinder, means for drawing off fabric knitted by the machine, comprising: a bush carried round by the revolving sinker ring, a substantially conical drawing-off surface on the said bush, a disc carried round by the revolving bush, a substantially conical drawing-off surface on the said disc, the knitted fabric passing between the two said drawing-off surfaces, the bush and the disc being so arranged that their conical surfaces can bear against one another so as to grip the fabric at one point, and means for resiliently urging the two drawing-off surfaces into contact with one another at the said gripping point, the bush and the disc being furthermore so arranged that when they rotate they roll one upon the other, and also undergo relative sliding motion, at the gripping point.

3. In a circular knitting machine comprising a needle cylinder, and a revolving sinker ring in the needle cylinder, means for drawing off fabric knitted by the machine, comprising: a bush carried round by the revolving sinker ring, a substantially conical drawing-off surface on the said bush, a disc, means for positively rotating the disc, a substantially conical drawing-off surface on the said disc, the knitted fabric passing between the two said drawing-off surfaces, the bush and the disc being so arranged that their conical surfaces can bear against one another so as to grip the fabric at one point, and means for resiliently urging the two drawing-off surfaces into contact with one another at the said gripping point, the bush and the disc being furthermore so arranged that when they rotate they roll one upon the other, and also undergo relative sliding motion, at the gripping point.

4. Means for drawing off knitted fabric from a circular knitting machine wherein individual articles are knitted in a continuous string, comprising: two rotatably mounted bodies with substantially conical surfaces of the same vertical angle between which the knitted fabric passes, the bodies being so arranged that their conical surfaces can bear against one another so as to grip the fabric at one position, and means for resiliently urging the bodies into contact with one another at the said gripping position, the bodies being furthermore so arranged that when they rotate their conical surfaces roll upon one another and also undergo relative sliding motion at the said gripping position.

5. Means for drawing off knitted fabric from a circular knitting machine wherein individual articles are knitted in a continuous string, comprising: two rotatably mounted bodies with substantially conical surfaces of the same vertical angle between which the knitted fabric passes, the axes of the said bodies being eccentrically arranged in relation to one another in such a manner that their conical surfaces can grip the fabric along a curved line, means for resiliently urging the bodies into contact with one another at the said gripping position, the bodies being furthermore so arranged that when they rotate their conical surfaces roll upon one another and also undergo relative sliding motion along the said curved line.

6. In a circular knitting machine comprising

loop-forming needles, means for drawing off fabric knitted by the machine, comprising: two rotatably mounted drawing-off bodies with substantially conical surfaces between which the knitted fabric passes, the drawing-off bodies being so arranged that their conical surfaces can bear against one another so as to grip the fabric along a curved line of contact, means for adjusting the drawing-off bodies in relation to one another in such a way as to vary the range and position of the curved line of contact in relation to the loop-forming needles, and means for resiliently urging the drawing-off bodies into contact with one another along the said line of contact, the bodies being furthermore so arranged that when they rotate their conical surfaces roll upon one another and also undergo relative sliding motion along the said curved line.

7. Means for drawing off knitted fabric from a circular knitting machine, wherein individual articles are knitted in a continuous string, comprising: two rotatably mounted drawing-off bodies with substantially conical surfaces between which the knitted fabric passes, one of these two conical surfaces being concave, the bodies being so arranged that their conical surfaces can bear against one another so as to grip the fabric at one position, and means for resiliently urging the bodies into contact with one another at the said gripping position, the bodies being furthermore so arranged that when they rotate their conical surfaces roll upon one another and also undergo relative sliding motion at the said gripping position.

8. Means for drawing off knitted fabric from a circular knitting machine wherein individual articles are knitted in a continuous string, comprising: two rotatably mounted drawing-off bodies with substantially conical surfaces between which the knitted fabric passes, one of these two conical surfaces being roughened by means of grooves, the bodies being so arranged that their conical surfaces can bear against one another so as to grip the fabric at one position, and means for resiliently urging the bodies into contact with one another at the said gripping position, the bodies being furthermore so arranged that when they rotate their conical surfaces roll upon one another and also undergo relative sliding motion at the said gripping position.

9. Means for drawing off knitted fabric from a circular knitting machine wherein individual articles are knitted in a continuous string, comprising: two rotatably mounted drawing-off bodies with substantially conical surfaces between which the knitted fabric passes, one of these two conical surfaces being coated with India rubber, the bodies being so arranged that their conical surfaces can bear against one another so as to grip the fabric at one position, and means for resiliently urging the bodies into contact with one another at the said gripping position, the bodies being furthermore so arranged that when they rotate their conical surfaces roll upon one another and also undergo relative sliding motion at the said gripping position.

10. Means for drawing off knitted fabric from a circular knitting machine wherein individual articles are knitted in a continuous string, comprising: two rotatably mounted drawing-off bodies with substantially conical surfaces between which the knitted fabric passes, the draw-

ing-off bodies being so arranged one above the other that their conical surfaces can bear against one another so as to grip the fabric at one position, the conical surface of the lower drawing-off body being smooth, the upper drawing-off body consisting of a carrier disc and an independent indiarubber ring mounted upon the carrier disc, the conical surface being on the indiarubber ring, the bodies being so arranged that their conical surfaces can bear against one another so as to grip the fabric at one position, and means for resiliently urging the bodies into contact with one another at the said gripping position, the bodies being furthermore so arranged that when they rotate their conical surfaces roll upon one another and also undergo relative sliding motion at the said gripping position.

11. Means for drawing off knitted fabric from a circular knitting machine wherein individual articles are knitted in a continuous string, comprising: two rotatably mounted drawing-off bodies with substantially conical surfaces, between which the knitted fabric passes, the bodies being so arranged that their conical surfaces can bear against one another so as to grip the fabric at one position, means for resiliently urging the bodies into contact with one another at the said gripping position, and means for separating the drawing-off bodies from one another at will while the machine is running, the bodies being furthermore so arranged that when they rotate their conical surfaces roll upon one another and

also undergo relative sliding motion at the said gripping position.

12. In a circular stocking-knitting machine comprising upper and lower needles and an appliance for disengaging and re-engaging the upper needles before and after knitting the heels and toes of the stockings, two rotatably mounted drawing-off bodies with substantially conical surfaces between which the knitted fabric passes, the bodies being so arranged that their conical surfaces can bear against one another so as to grip the fabric at one position and means for resiliently urging the bodies into contact with one another at the said gripping position, means for separating the drawing-off bodies from one another at will while the machine is running, the said means for separating the drawing-off bodies being actuated by the said needle engaging and disengaging appliance.
